RECORDING DEVICE

James W. Bryce, Glen Ridge, N. J., assignor to
 International Business Machines Corporation,
 New York, N. Y., a corporation of New York

Application January 13, 1942, Serial No. 426,550

13 Claims. (Cl. 95—4.5)

This invention concerns an improved record-controlled photographic recorder.

One object of the present invention resides in the provision of improved means for effecting exposure of character under the control of record card analyzing means.

More particularly, it is an object of the present invention to provide improved inertialess exposure effecting means brought into action under the control of record analyzing means whereby the use of mechanical shutters may be obviated.

An object of the present invention resides in the provision of a photographic recorder employing gaseous discharge tubes as exposure effecting means with provisions for cyclically timing the firing of such tubes to effective selective exposure operation.

A further object of the present invention resides in the provision of improved means to obtain high potentials for effecting tube firing from a low voltage source of current supply.

Further, an object of the invention resides in the provision of condenser means to supply high voltage firing potential for the gaseous discharge tube to effect photographic exposure of selected indicia, with such condenser means being charged by the comparatively low voltage source of current supply.

More particularly, it is an object of the present invention to provide circuits and switching means and sets of condensers with provision for charging the condensers in parallel when connected to a low voltage current supply and for thereafter reconnecting the condensers in series relation and discharging them to effect firing of a gaseous discharge tube.

Another object of the invention resides in the provision of means to detect failure of a selected exposure-effecting element to function properly.

More particularly, an object of the invention is to test the gaseous discharge exposure-effecting tubes for proper functioning when such tubes have been selected for exposing desired indicia to a film.

Further, an object of the invention is to indicate which of a plurality of the gaseous discharge tubes selected for operation has failed to function.

An object is also to interrupt operation of the machine automatically upon failure of the selected exposure-effecting element or elements to function properly.

More specifically, an object of the invention resides in the provision of tube failure detecting means operated by discharge of the condenser means when such condenser means have failed to discharge through the gaseous discharge exposure-effecting tubes.

Another object of the invention resides in a novel arrangement and mounting for a bank of 60

gaseous discharge tubes within a rotatable translucent or transparent character bearing drum having columns of characters, each column associated with one tube.

5 Further and other objects of the present invention will be hereinafter set forth in the accompanying specification and claims and shown in the drawings which show by way of illustration a preferred embodiment and the principle thereof and what I now consider to be the best mode in which I have contemplated applying that principle. Other embodiments of the invention employing the same or equivalent principle may be used and structural changes made 10 as desired by those skilled in the art without departing from the present invention and within 15 the spirit of the appended claims.

In the drawings:

Figures 1 and 1a taken together, with Fig. 1a 20 to the right of Fig. 1, show a perspective view of the improved machine;

Fig. 2 is a sectional view of the camera unit. The section is taken substantially on lines 2—2 of Fig. 4.

25 Fig. 3 is a sectional view of the recording section of the machine. The section is taken substantially on lines 3—3 of Fig. 1.

Fig. 4 is a similar view with the section taken on a different plane, i. e., on lines 4—4 of Fig. 1;

Fig. 5 is a detailed sectional view showing the drum and the drive train thereto. The section is taken substantially on lines 5—5 of Fig. 4 and to larger scale;

30 Fig. 6 is a detailed sectional view taken on lines 6—6 of Fig. 5 and shows the mountings for the neon tubes within the drum;

Fig. 6a is a detail view of a tube mounting on a larger scale than in Fig. 6;

Fig. 7 is a detailed sectional view of the card 35 feeding section of the machine, the section being taken substantially on lines 7—7 of Fig. 1a;

Fig. 8 is a timing diagram;

Fig. 9 is an enlarged view of a section of the film showing the characters as recorded thereon 40 after development of the film;

Fig. 10 is a perspective view of the character carrying drum;

Fig. 11 shows a development of the drum for one complete column of characters; and

Fig. 12 shows a circuit diagram.

Referring now particularly to Figs. 1 and 1a, the machine in general comprises a record handling and record reading section which is shown to the extreme right in Fig. 1a. In Fig. 1 there is shown the recording section of the unit in the machine. Suitable shafting connects the recording section and the record handling and analyzing section. On Fig. 1a, 20 is the driving motor. This motor through the usual worm gearing and shafts is adapted to drive a main drive shaft 21.

This main drive shaft 21 directly drives parts in the recording section as will be subsequently described. It also drives the so-called C cams. Fast on shaft 21 is a gear 22 which drives a gear 23. Fast to gear 23 is a one-revolution clutch element 24 which is freely rotatable on shaft 25. The clutch dog 26 is carried by the member 27 which is fixed to shaft 25. Pawl 26 is adapted to be tripped into engagement with the notch in element 24 upon energization of card feed clutch magnet 28. Driven by and secured to shaft 25 are two distributing commutators CD₁ and CD₂. Also fast to the shaft are a number of card feed cams CF₁ through CF₈, inclusive. Gearing 29 transmits drive from shaft 25 to the main drive shaft 30 of the card handling and reading unit. This card handling and reading unit is the customary construction including the usual supply magazine 31 and a stacker or discharge magazine 32. This unit also is provided with driven card feed rolls 33 (see Fig. 7), these rolls being driven by the helical gearing shown in Fig. 1a. Cooperating with the driven rolls and geared therewith are upper rolls 34. 35 is a conventional picker driven from picker drive shaft 36, this shaft in turn being driven from the drive shaft 30 by the helical gearing shown in Fig. 1a. B₁ (Fig. 7) are advance sensing brushes and B₂ are the regular or main sensing brushes. These cooperate with contact rolls 37 and 38 respectively. 39 and 40 are card levers which when cards are present close card lever contacts 41 and 42 respectively. The operation of the record handling unit will be readily understood. When the card feed clutch magnet 28 (Fig. 1a) is energized, shaft 30 is set in rotation, the picker 35 withdraws a card from the magazine 31, advances it to the driven feed rolls and thereafter the feed rolls continuously feed the card first to the advance brushes B₁, thereafter to the regular brushes B₂ and finally into the stacker 32.

Recording section

Referring to Figs. 3 and 4, the recording section includes a suitable base 45 which has fast thereto a pair of side plates 46 and 47. Suitable bearings in plate 46 (see Fig. 5) afford a journal for the end of drive shaft 21. The drive shaft 21, through gearing generally designated 48, is adapted to drive a drum driving gear 49. This drum driving gear 49 is suitably fixed to one of the end hubs 50. Hubs 50 are rotatably mounted in bearings 51 supported in plates 46 and 47. Fast to the hub sections 50 are annular members 52 which support the character carrying drum 53. The drum 53 may be made of any suitable transparent material such as a transparent plastic. The drive gearing which drives the drum is preferably proportioned so that the drum 53 will make one complete revolution during three machine cycles, that is to say, if three cards in succession pass the regular brushes during the transit of these three cards there will be one complete revolution of drum 53. This drive relation is for convenience in design. The cylindrical drum is preferably opaque on its surface, except at the character displaying portion where the drum is transparent or translucent. As stated before, the drum is preferably made of a synthetic translucent or plastic material to avoid the possibility of breakage. This cylinder is thereafter covered with an opaque surface except at the character displaying portions. These character displaying portions may be termed character patterns.

In the drawings, for clarity of illustration, the characters are shown opaque and the drum transparent, but in actual practice the characters would be transparent and the background surface opaque. The drum is provided with a plurality of columns of characters, one such column being shown in Fig. 11. This column of characters comprises three sets of digits from 9 through 0, inclusive. With the drum in continuous rotation, i. e. rotating in the direction of the arrow in Fig. 10, the various digital characters are successively presented to an exposing position. With the drum in normal home position no character will be at the exposing position. Then if the drum commences rotation the first character to be brought to the exposing position would be the digit 9, the next the digit 8 and so on.

Disposed within the drum are a plurality of 20 gaseous discharge tubes such as neon tubes. Normally these tubes are not lit. When it is desired to record a character a source of potential is momentarily applied to the neon tube at the instant the desired character is in proper position 25 for recording. The bright light from the neon tube will trans-illuminate the character and such character will be recorded on the film as will be subsequently explained. Since the drum hubs 50 are hollow, it is possible to provide supports extending from the outside of the drum through the hubs and into the interior of the drum to support the neon tubes therein. A cable may be also led into the interior of the drum through one of the hollow hubs. Such cable affords the 30 connective wires to provide current to the individual neon tubes. 58 designates an individual neon tube. Such tube (see Fig. 6) is generally U-shaped. Its terminal ends fit into conductive socket elements 56 which are molded in a block 35 of insulating material 55, the block being supported by brackets 54. Spring pressed balls 59 (see Fig. 6a) retain the tube in position in its conductive socket elements. The rear of each socket element receives the plug tip connected to the 40 wire in the cable 64. Insulating separators 61 are provided between the tubes to prevent illumination from a tube related to one column to effect other columns. It will be understood that a single neon tube is provided for each column of 45 characters on the drum. A mask 62 with a central slot 63 is interposed between the drum and the camera unit so that only a single line of 50 characters will be photographed at a time.

Camera unit

Referring to Fig. 4, a strap 65 is fastened to the end plate 46 and bridges the notch therein. Plate 46 and plate 47 (Fig. 3) are provided with upper notches to receive transverse bars 66. To one of these transverse bars there are attached a pair of inclined frame members 67. These frame members and bars 66 provide a support for a housing which is generally designated 68. One wall of the housing comprises an apertured plate 69 which is secured to a bracket 70 fast to the base 45. Plate 69 is also secured to the member 67. Supported on plate 69 in any suitable manner, as by welding, is a dished member 71 which in turn carries a smaller dished channel member 72. Camera housing 73 fits between the rims of the members 71 and 72 and the camera housing may be secured in place in any suitable manner as by the thumb screws 74. The main camera frame plate 75 is suitably secured to the 70 member 71 (see Fig. 4). Plate 75 carries a stud 75

16 rotatably mounting a film supply spool 77 (see Fig. 2). Frame plate 75 also has mounted thereon three rotatable shafts 78, 79 and 80, having fixed thereon film feed sprockets 81, 82 and 83 (see Fig. 3). These sprockets are adapted to fit the film which is provided with the usual sprocket holes. A take-up spool 84 is provided for the film, this spool being mounted on a rotatable shaft 85.

Film feed is effected upon energization and successive de-energization of a film feed solenoid 86 (see Figs. 2 and 4). Energization of this solenoid lowers a linkage 87 which carries a feed pawl 88. This pawl is engaged with a ratchet wheel 89 which is fast to a pinion 90. Ratchet wheel 89 and gear 90 are rotatably mounted on a stud 91. Gear 90 meshes with a gear 92 which has fast to it a smaller gear 95. Gear 95 in turn meshes with a gear 96 which is fixed to the shaft 79 which drives sprocket 82. Gearing 97 also transmits drive to the upper sprocket shaft 78. Gearing 98 also drives the lower sprocket shaft 80. The lower sprocket shaft 80 carries a pulley which through a belt 99 drives a pulley fixed to the takeup spool shaft 85. Energization of the solenoid 86 lowers the linkage 87 and the pawl 88 carried thereby. Upon de-energization of the solenoid 86, a spring 100 restores the linkage and pawl to normal position. During the restoring motion of the pawl it rotates the ratchet wheel 89 for one step of advance. Such step of advance of the ratchet wheel through the drive connections previously described drives the various sprocket wheels and the takeup spool and advances the film one line space. The shaft 80 which carries the lower sprocket wheel 83 is slotted at one end to receive a winding key 101 (see Fig. 2). This winding key is normally disposed in the retracted position as shown. This winding key is used to wind up the film on the takeup spool when the camera is being loaded and upon removal of film from the camera unit.

Referring to Fig. 3, a spring pressed lever 102 rests in contact with the film on the supply spool. When the film on the supply spool nears the end of the roll, the lever 102 will swing to a position in which contacts 103 are permitted to open. In a manner which will be subsequently explained the opening of these contacts terminates the operation of the machine.

Referring to Fig. 3, the member 11 provides a support for a lens and shutter assembly generally designated 104. 105 is the shutter operating member of the shutter assembly (see Fig. 4). The shutter of this shutter lens assembly is adjusted for a so-called bulb exposure operation. It may be mentioned that the shutter is intended to be open and left open during recording and to be manually closed when the recording unit is open for inspection and repair. The shutter of this shutter assembly is opened by moving shutter operating member 105 upwardly and the shutter is closed upon return of the member to lower position. As shown in Fig. 4, the member 105 is in upper position. Part 106 abuts the top of a slide 107 having a pin and slot connection to a lever 108. Lever 107 is in turn fast to a pivot 109. One end of this pivot (see also Fig. 2) is slotted for engagement with a key 109. With the parts in the position shown in Fig. 4, the lever 107 is at its counterclockwise limit and the connected slide 106 is in upper position in which it holds the shutter operating member 105 in shutter opening position. In the other position of the parts, the lever 107 is in clockwise displaced posi-

tion and the connected slide 106 is in lower position in which it permits part 105 to move to shutter closing position. A spring actuated impositive detent 110 coacts with the left hand end of lever 107 to maintain this lever in either of its two positions. Operation of the shutter accordingly may be effected by manipulation of key 109.

Circuit diagram

10 Before the machine is started up to effect recording operations pertaining to a run of cards, certain plug connections must be first made. Assuming that auto-control is desired on several classification columns, plug connections are established from the plug sockets 115 wired to the advance sensing brushes B1 for these card columns to the sockets 116 which are connected to the pickup coils p of the usual duo wound auto-control relays A. Other plug connections are made from sockets 117 of these same pickup coils to the double sockets 118 which are wired to the regular sensing brushes B2 for the classification columns. If two columns, for example, are to be used for auto-control, two pickup coils of relays 20 A are plugged up in this manner and plug connections also are made from a pair of the 119 sockets to the 120 sockets which are wired to contacts A2 of the two utilized A relays. The number of connections between 119 and 120 depend upon the number of columns which are plugged up for auto-control.

Other plug connections are made from desired ones of the sockets 118 of the B2 brushes to sockets 121 which connect to relay coils generally designated E. It will be understood that one of these relay coils E is provided for each column of recording but for simplicity in the circuit diagram only a few of such coils are shown. The circuits which will be made through coils E are 30 the sensing circuits to be closed by sensing of character designations to control recording of designated characters. The current supply for these sensing circuits is at relatively low line voltage. On the other hand, with the present machine, the neon tubes are fired with current 40 at a relatively high voltage and it is desirable that the high voltage circuits be isolated from the sensing circuits. Accordingly, the relay coils E are utilized, these being energized under line voltage applied through the card sensing circuits. 45 50 These relays E in turn are utilized to connect up the neon tubes to receive high voltage current and to be fired for recording as will be subsequently explained.

The opposite terminals of each individual neon tube 58 are connected to plug sockets 122 and 123. A plug connection is made from the 123 socket of a tube to a 124 socket and another plug connection is made from the 122 socket of the tube to a 125 socket. It will be understood that 55 as many neon tubes are utilized as are necessary for the required number of columns to be recorded. In practice there is one neon tube for each column of characters upon the drum and while only a few neon tubes have been shown in the circuit diagram for simplicity of illustration, it will be appreciated that more are provided. Other plug connections are made from sockets designated 126 to sockets 127. The latter plug connections are in the charging circuits of certain condensers commonly designated K.

It may here be mentioned that with the present machine exposure of variable data from the character carrying drum 53 is effected by flashing the 70 neon tubes at the proper differential time. Such

neon tubes require considerable voltage to flash or fire them. In order to provide such voltage, according to the present invention, use is made of sets of condensers K, one set of condensers being provided for each column of data to be recorded and each such set being plugged up to one neon tube. In general, it may be stated that the condensers are charged from the relatively low voltage D. C. supply line with the condensers of each set connected in parallel. Accordingly, each condenser of the set will be charged to approximately the line potential of the D. C. supply line. After the condensers are thus charged and before recording, provision is made for reconnecting the condensers of each set in a series relation. With the condensers connected serially a high potential is available for flashing or firing the related neon tube.

It will be further appreciated that if a neon tube associated with a drum column should fail to fire for any recording operation, the result would be that there would be no exposure on the film for that particular column. With such a tube failure, many lines of film might be run through the machine before the tube failure was detected because it would only be after the film had been removed, developed and examined that the tube failure would be apparent or detected. To prevent such undesired operation, testing and indicating means are provided. While this testing and indicating means will be subsequently described in greater detail, its general principle of operation may be mentioned here. If a particular neon tube fails to fire during a cycle, its related bank of firing condensers will retain a charge after the recording period of the cycle. This retained charge is utilized to energize a testing relay. If such a testing relay becomes energized, an indicating lamp pertaining to the particular column of undischarged condensers is illuminated and further the machine operation is automatically terminated. Since the operator knows which particular neon tube is plugged to the undischarged condenser column, the illumination of an indicating lamp indicates which neon tube is defective and has failed to fire. On the other hand if a set of condensers after recording operations retains no charge, the testing relays will not be energized, the indicating lamp or lamps will not be illuminated and the machine operation will be permitted to continue. Tests have demonstrated that relatively short small neon tubes can be fired reliably with an applied voltage in the neighborhood of 1000 volts. While firing may occur at relatively lower voltages such as in the neighborhood of 750 volts, the firing is not as reliable at such lower voltages. Tests have also shown that when using a direct current supply of 110 volts, proper firing voltage can be obtained by using ten condensers each with a capacity of .25 microfarad and with such condensers connected in series for firing and in parallel for charging. Tests have also demonstrated that a character image can be sharply recorded on a photographic film such as a panchromatic XX film with a lens system operating with an aperture 4.5f and deriving light from a neon tube fired at approximately 1000 volts and with the light from the tube passing through a character carrying drum under the following operating conditions. The drum diameter was 3.82". It was adapted to be provided with three successive sets of numerical characters disposed about its periphery as generally indicated in Figs. 10 and 11. The drum was rotated at 200 revolutions per

minute. Under these conditions of operation the film upon development disclosed clearly defined character images. There was no appreciable blur or distortion. Tests have demonstrated that 5 neon tubes of this type are capable of being brought up to intense illumination and completely extinguished in an extremely short time which is, however, sufficient to effect film exposure.

The above conditions of operation show that 10 numerical recording speeds of 600 cards per minute can be attained. The attainable speeds obviously can be increased by providing faster lenses, faster films, etc. Under numerical recording conditions, 48 index points on the drum pass per 15 revolution. At 200 revolutions per minute 9600 index points pass per minute or any index point passes the exposure position in $\frac{1}{160}$ of a second. Tests have further demonstrated that a neon tube can be fired utilizing a commutator to establish the circuit to the tube and accurately time the firing circuit, with the commutator completing a circuit for a period of approximately $\frac{1}{1200}$ of a second. With such timing of tube firing, effective exposure was obtained and the condensers substantially discharged to a point where 20 retained charge if present at all, was insufficient to energize the related testing and detecting relays.

Assuming the proper perforated records are 25 in the supply magazine 31 (Fig. 7), the operator of the machine first closes main line supply switch 128 (Fig. 12) providing D. C. current supply to buses 129 and 130. The start key is now depressed, closing start key contacts 131 to complete 30 the following circuit: from left line 129, through the serially connected D1 contacts of the various detecting and testing relays D, through the master auto-control contacts G1, through the start key contacts 131, through the film lever contacts 103 and through the card feed clutch magnet 28 to the other side of the line 130. A branch circuit is also completed through a holding relay H which on energization closes contacts H1. Energization of magnet 28 starts card feeding in the customary 35 manner and the card is advanced from the supply hopper and in the first machine cycle reaches a position in which its leading edge is under brushes B1 in which position card lever contacts 41 are closed. Closure of these card lever contacts causes 40 energization of relay coil M, closing contacts M2 to provide a stick circuit for the coil through cam contacts CF1. Coil M also closes contacts M1. These M1 contacts and the stop key contacts and now closed contacts H1, shunt the start 45 key contacts 131 so that the start key may now be released and the machine will continue in automatic operation until cards are exhausted or a change in card group occurs. During the second card cycle, the first card is fed to a position in 50 which it causes the second card lever contacts 42 to close. Accordingly, coil N is energized, closing contacts N1 which are in shunt with contacts M1. Coil N also closes contacts N2 to provide a stick circuit for the coil by way of cam contacts 55 CF2. The stick circuits for these relay coils M and N are provided so as to maintain the coils energized during the intervals in which the card lever contacts open between successive cards.

During the third card cycle, the first card will 60 be sensed by the B2 brushes and the second card will be sensed by the B1 brushes. At the beginning of this third cycle, a charging circuit is established to the condensers K. As explained before, there are ten condensers in each set. 65 With card lever relay coil N energized, relay

contacts N3 are closed and a circuit is established from left line 129, through N3, through a commutator timer CD1 to a line 132, thence through a resistor in parallel through the normally closed switching contacts R2 and the various K condensers of the set, thence out through the normally closed S2 switching contacts to a line leading to plug socket 126, thence via the plug connection to 127 to the line which extends to the opposite D. C. line 130. As soon as the various sets of condensers are charged, provision is made for reconnecting the condensers from their parallel charging relation to a series relation. Closure of cam contacts CF6 at the time shown in the timing diagram establishes an energizing circuit for relays R and S. With these relays energized, the contacts R2 and S2 open and the contacts R1 and S1 close. With the latter contacts closed, the several condensers K of each set are connected in series relation.

It may be here mentioned that there is a CD1 timing commutator for each of the sets of condensers and all of the sets which have been connected to line 130 through plugging between sockets 126 and 127 are concurrently charged.

During the third machine cycle, the leading card is sensed, the recording control magnets E are energized, and the auto-control circuits are set up.

Assuming that the cards under the brushes have agreeing group designating perforations, the auto-control circuits are established as follows: from left side of line 129, through the M3 relay contacts, cam contacts CF9 to common conductor roll 37, thence through the B1 brushes sensing the group perforations, thence through the plug connections between sockets 115 and 116, through the pickup coils p of auto-control relays A, thence through the plug connections from 117 to 118, back through the B2 brushes to the 38 contact roll 38, through CF1 cam contacts, through relay contacts N4 and back to the D. C. line 130. The auto-control magnets A are of the usual dual winding type and the energized pickup coils close the stick contacts A1 to energize the companion holding coils h through circuits extending from line 129, through cam contacts CF4. The energized A magnets open the related A2 contacts so as to prevent energization of master auto-control relay coil G. It may be pointed out that if the cards do not have corresponding group perforations, then the A2 contacts will remain closed and upon closure of cam contacts CF8 near the end of the cycle, the circuit of coil G will be established via relay contacts N5. Coil G will then open contacts G1 to break the card feed clutch magnet circuit.

The relay coils E are energized under the control of the B2 brushes as they sense the usual Hollerith character designating perforations in the card in columns where recording is desired. The circuits are from line 130, through the N4 contacts now closed, the CF7 contacts to contact roll 38, thence through B2 brushes, through the plug connections from 118 to 121, through the relay coils E and back to the D. C. line 129. It will be understood that the relays E are energized at differential times in accordance with the differential positions of the holes in the records. Relay coils E only energize momentarily but upon energization, they close their related E1 contacts. With such E1 contacts closed, a flashing circuit or circuits is established as will now be described.

From the right hand terminal of the lowest K 75

condenser of a set, for example, the left hand set in Fig. 12, through the condenser, thence through the wire which extends to the second S1 contacts from the bottom of the now closed S1 contacts, then through the next condenser and so on in succession in series through the various condensers and the S1 contacts, finally through the uppermost condenser, through the now closed R1 contacts, through the plug connection between plug sockets 124, 123, thence through the neon tube 58, through the plug connections between sockets 122 and 125 via downwardly extending wire, through the now closed E1 contacts, through a timing commutator CD2, via wire 133, back through a resistor 134, through the lowest S1 contact and back to the starting point.

It will be understood from the foregoing that the condensers discharge through the neon tube 20 when the condensers are connected in series relation.

It may be here mentioned that the commutator CD2 is timed for a very short duration of circuit disclosure, which duration is sufficient to fire the tube and effectively expose the passing 25 character of a character column on the drum to the film in the camera unit.

It will be understood that while the circuit has been traced for one particular column of condensers and for one neon tube, exposures may 30 occur for a multiplicity of columns.

It will be understood that the related character 35 on the drum is passing the exposure position at the time the related neon tube is illuminated under control of the corresponding index point in the card and the commutator contacts CD2 close for a short period of time in which the said index point is being sensed. The characters selected by the designations in the card columns can thus be exposed and recorded at differential points of the cycle and such exposure for different columns may occur either concurrently or at different differential times depending on whether like or unlike designations are 45 sensed in the card columns. Exposure during a card cycle of characters in different columns will, however, be effected on a common line on the film.

After exposure, film feed may be effected. 50 Upon closure of cam contacts CF3 a circuit is completed from line 130, through relay contacts N6 now energized, through the CF3 contacts and through film feed solenoid 86 (also see Fig. 4). Energization of the solenoid followed by its subsequent deenergization upon opening of cam contacts CF3 causes line spacing of the film in the manner previously described.

Provision is now made for detecting proper 60 operation or more exactly, mis-operation of the neon tube or tubes. If a tube fails to fire there will be a charge remaining in the condenser bank pertaining to that particular tube which failed to fire.

Before testing is effected, relays R and S are 65 deenergized by opening of cam contacts CF6. Accordingly, R2 and S2 contacts reassume the normal relation shown in the wiring diagram. Assuming a charge remaining in one or more of the condensers K, current will flow from the charged condensers through the R2 contacts now closed, to a line 135, thence through relay contacts N7 now closed, through cam contacts CF5, which close at the time shown in the timing diagram, through one of the detecting relay coils D, through a resistor 136, up through the S2 con-

tacts to the opposite sides of the charged condenser. The energy in the circuit thus established is sufficient to energize the D coil, closing related contacts D2 to establish a circuit through key contacts 137, through an indicating lamp 138, through the D2 contacts, through the D relay coil, through resistor 136, through a plug connection from 126 to 127 and back to line 130. It may be here mentioned that there is a lamp 138 for each condenser column (see also Fig. 1). The operator can therefore detect by the particular lamp 138 which is illuminated, the particular condenser column and the plugged-in neon tube for which there has been a tube failure. The energization of relay D also has opened its related D1 contact and the opening of such D1 contact interrupts the holding circuit to the card feed clutch magnet 28, causing de-energization of the card feed clutch magnet and stopping further feed of cards through the card handling section of the machine. After there has been a tube failure, the operator detects which tube is faulty, replaces it and then provision is made for opening up the signal or warning circuit through lamp 138 and related coil D. Opening up of such circuit for relay D and circuit lamp 138 is afforded by manual operation of the key which controls normally closed key contacts 137.

With the present machine, when a change in control occurs between card groups, provision is made for effecting additional film feed to give distinct spacing between the successive different groups. When successive cards with the disagreeing group perforations traverse brushes B1 and B2, one or more of the auto-control magnets A are not energized and the related A2 contacts remain closed and when the CF8 contacts close, coil G is energized as explained before, through the closed A2 contacts and the N5 contacts. Coil G closes stick contacts G2 providing a stick circuit for the coil, through cam contacts C1. Energization of coil G also opens contacts G1 to break the card feed clutch magnet circuit, causing interruption in card feed. Coil G also closes contacts G3, establishing a circuit from line 130, through these contacts, through cam contacts C2 when closed, then through the film feed magnet 86 to line 129. Upon opening of cam contacts C2, the circuit just traced is broken and magnet 86 de-energized. As a result the film is line-spaced. Coil G is still energized and contacts G3 still closed when cam contacts C3 close. Contacts C3 function to the same effect as contacts C2. Hence a second energization and de-energization of magnet 86 occurs, causing a second line spacing of the film. Following this supplemental line spacing operation, provision is made for automatically re-initiating card feed. Re-initiation of card feed is effected as follows: With relay contacts G4 now closed, the closure of cam contacts C4 completes a circuit from line 129, through G4, C4, to and as before, through the card feed clutch magnet 28 and coil H. Card feed of records pertaining to a following group will now automatically be resumed.

On last card operations, there is, in effect, a break in auto-control, causing stopping of the machine operation. This break in control is due to the fact that relay contacts M3 are now open and no circuit is provided to contact roll 37.

What is claimed is:

1. In a photographic recorder with a continuously movable character carrying drum, having a plurality of columns of characters, the characters in a column being arranged in sets, the

combination of means without the drum for supporting a photographic medium in position for exposure, means for selectively exposing the characters on the drum upon said medium, said exposing means including a plurality of gaseous discharge tubes one for each column of characters, said tubes being fixedly disposed within the drum and means for firing each tube only once at a selected differential time during the transit of a set of characters past the photographic medium, each tube upon being fired trans-illuminating the drum and exposing a single character once to the photographic medium for the purpose described.

2. A cyclical machine operating in successive cycles on record cards having parallel columns of character designations, each card column designating a character, comprising in combination, photographing means to provide successive picture lines of multi-column characters on a film, sensing elements, one for each card column, means for continuously feeding one card each cycle past the sensing elements to be sensed concurrently in the parallel columns for designations, a character bearing drum with a light-pervious periphery having parallel columns of character patterns, each drum column including a set of circumferentially spaced different character patterns, with like character patterns of the different drum columns being arranged in alignment parallel to the axis of rotation of the drum, mechanism for rotating the drum continuously in one-to-one synchronism with the fed of a card past the sensing elements so as register the different character patterns of the drum columns with a photographing position at successive differential times of a cycle, a bank of gaseous discharge tubes inside the drum, masking devices for masking each tube from the others, each of such tubes being disposed behind a drum column, high voltage firing circuits, one for each tube, controls, one for each circuit operable to render the circuit of a tube operable at a differential time of the cycle, means controlled by the sensing elements according to the designations sensed in a plurality of card columns during a cycle for rendering the related controls transiently effective to cause the circuits to operate for flashing the tubes at the differential times in which the character patterns corresponding to sensed designations are registering with the photographing position with like character patterns of different drum columns being thereby exposed concurrently and unlike characters at successive differential times to the same line of the film, film line spacing means, and cyclic means operating in the interval between the sensing of successive record cards for causing the line spacing means to effect film line spacing, whereby successive lines of multi-column character patterns are photographed upon the film, one such line for each sensed record card.

3. Exposure effecting means for exposing a selected character derived from a continuously movable rotatable drum to a photographic medium, said exposure effecting means comprising a gaseous discharge tube with means for firing it, said firing means comprising a set of condensers adapted to receive a charge, means for connecting said condensers in parallel to receive said charge from a low voltage source supply, means for reconnecting said condensers in series preparatory to firing a tube, and means for connecting said series-connected condensers to said

tube at a differential time in the rotation of the drum to fire said tube.

4. In a photographic recorder, in combination, a gaseous discharge tube and means for firing it for effecting a photographic exposure, said firing means including condenser means adapted to receive a charge and adapted to discharge through said tube to fire it, means to detect the failure of a tube to fire, said detecting means including testing means to test the condenser means for the presence of a charge after attempted firing of a tube and manifesting means controlled by said testing means to manifest that a tube has failed to fire.

5. The invention according to claim 4, wherein in the photographic recorder includes a plurality of such gaseous discharge tubes and wherein the testing means includes means to test each of the tubes and wherein the manifesting means includes a plurality of indicating means which indicate the tube or tubes of the plurality of tubes which fail to fire.

6. A record controlled machine, including means for feeding records one by one in succession, means for analyzing each record for data designations therein, a photographic recorder including a gaseous discharge tube which is fired under the control of the record analyzing means to effect a photographic exposure, detecting and testing means for determining the failure of a tube to fire and means controlled by said detecting and testing means for supervising feed of the records.

7. A record controlled machine, including means for feeding records one by one in succession, means for analyzing each record for data designations therein, a photographic recorder including a gaseous discharge tube which is fired under the control of the record analyzing means to effect a photographic exposure, detecting and testing means for determining the failure of the tube to fire and means controlled by said detecting and testing means for manifesting that the tube has failed to fire.

8. The invention according to claim 1, wherein the tube firing means includes condensers, means for connecting said condensers in parallel to a low voltage source of current supply to be charged thereby, means thereafter reconnecting said condensers in series preparatory to firing a tube, and means including cyclically operable means and coacting record-controlled means for connecting the serially connected condensers to a tube for a short period, and at a differential time during the rotation of the drum.

9. A machine as defined in claim 1, said firing means for the tubes comprising high voltage circuits, condenser means for supplying high voltage to the circuits, and means for charging the condenser means cyclically from a low voltage source.

10. In a machine of the kind described, a rotating drum with a light-pervious periphery bearing parallel columns of character patterns, exposure effecting means for the character patterns comprising a bank of gaseous discharge tubes, one for each column, record-controlled circuits selectively timed to fire the tubes to expose selected character patterns of the drum columns at an exposure position, an insulating common support inside the drum and having sockets for

mounting the bank of tubes, masking devices between the tubes secured to and extending from the said support, said drum having a hollow hub enabling wiring for the tubes to extend from outside the drum through the hub into the interior of the drum to connect to the tube sockets.

11. In a photographic recorder including a continuously rotatable drum with a light-pervious periphery provided with parallel columns of character patterns, each column including a set of different character patterns successively traversing an exposure position during a cycle, the combination therewith, of means to support a light sensitive medium outside the drum in position to record exposed character patterns, exposing means comprising a plurality of gaseous discharge tubes, one for each drum column, fixedly disposed inside the drum, and means for firing the tubes including high voltage circuits and automatic timing means for the circuits including character pattern selecting means for the several drum columns for variably determining differential times of the cycle for closure of the circuits, with such selecting means for each column automatically effecting a new determination of differential times for closure of said circuits each cycle, whereby the same or different character patterns from a drum column are selected to be exposed in successive cycles, said tubes upon being fired by closure of the related high voltage circuits at selected differential times of the cycle trans-illuminating the drum to expose the character patterns passing the exposure position within the same or successive selected differential times of a cycle to a common line of the light sensitive medium.

12. In a photographic recorder which includes in combination, a gaseous discharge tube which upon being fired effects a photographic exposure upon a photographic medium, a firing circuit for said tube, a bank of condensers, means of charging them in parallel, means for subsequently reconnecting the bank of condensers in series preparatory to firing the tube, and means for connecting the condensers to the firing circuit to effect tube firing while the condensers are serially connected wherein the means for connecting the condensers to the firing circuit includes timing means for timing the duration of the connection and providing for connection at different differential times and a co-acting differentially controlled selecting means for determining at which different differential time a tube is to be fired.

13. In a photographic recorder, a gaseous discharge tube which upon being fired effects a photographic exposure upon a photographic medium, a firing circuit for said tube, a bank of condensers, means for charging them in parallel, means for subsequently reconnecting the bank of condensers in series preparatory to firing the tube, and means for connecting the condensers to the firing circuit to effect tube firing while the condensers are serially connected, the means for connecting the condensers to the firing circuit including selecting means to select one of successive differential intervals of a cycle in which the tube is to fire and including also timing means for exactly timing the duration of the connection of the condensers to the firing circuit during the selected interval.

JAMES W. BRYCE.
